UNITED STATES PATENT OFFICE.

ALFRED T. JACKSON, OF HICKORY GROVE, KENTUCKY.

WASHING-MACHINE.

SPECIFICATION forming part of Letters Patent No. 321,031, dated June 30, 1885.

Application filed June 3, 1884. (No model.)

To all whom it may concern:

Be it known that I, ALFRED T. JACKSON, a citizen of the United States, residing at Hickory Grove, in the county of Graves and State of Kentucky, have invented certain new and useful Improvements in Washing-Machines; and I do hereby declare the following to be a full, clear, and exact description of the invention, such as will enable others skilled in the art to which it appertains to make and use the same.

The object of this improvement is a cheaply-constructed, easily operated, and efficient washing-machine. This result is attained by the mechanism illustrated in the drawings, herewith filed as part hereof, in which the same letters of reference denote the same parts in the different views.

Figure 1 is a plan with the cover partly broken away. Fig. 2 is a side elevation partly in section.

A is the tub. B and B' represent the supporting-frame. C C' represent the cover made in sections.

D is a metal plate secured to the cover-section C by bolts *d*, and having an elevation, D', and an arm or extension, D''. The elevation D' of the plate D with the extension D'' forms a way or guide for the reception of a rack-bar, F. The latter is provided with a slotted eye, *f*, connecting with a pitman, G, which has a slotted eye, *g*, between which is pivoted the operating-handle end *H* of the lever *H*'.

The said lever is arranged vertically with the tub, and has its lower end pivoted to a slotted plate, *H*', which is secured to the bottom of the tub by any suitable means.

c c are metal pins or staples set into the lid-section C for the purpose of securing the same to the tub A by means of the hooks *a*.

E is a shaft secured in position through corresponding opening in the cover-section C and arm D'' of the plate D D'.

E' is a pinion rigidly secured to the shaft E, and meshes with the rack-bar F.

J is a disk secured by any suitable means to the lower end of the shaft E, and provided with a series of perpendicular extensions or pins, K, for the purpose hereinafter set forth.

50 The tub A is to be lined with zinc or other sheet metal, in order to make the same watertight, or the same result may be obtained by any sufficient construction or means.

Reciprocal motion given to the handle H will operate the disk J through the rack-bar 55 F and pinion E', and the pins K will engage with the garments in the tub and give them such motion through and friction against the suds and each other as will thoroughly cleanse them without injuring their texture. 60

It will be observed that the peculiar construction of the plate D with the elevated part D' and the perforated arm or extension D'' enables said plate to serve both as a guide or housing for the rack-bar and also as a bearing for the pinion-shaft E. 65

Having explained the construction and operation of my improvement, what I claim as new, and desire to secure by Letters Patent, is—

70 1. In a washing-machine, the combination, with the tub suitably supported and provided with a top or cover, of the vertical shaft E, journaled therein, depending into the tub and carrying an agitator within the same, the plate 75 or casting D, secured to the cover and formed with the raised portion or elevation D', and the perforated arm or extension D'', the latter providing a bearing for the upper end of the shaft E, a pinion, E', fitted thereon, the rack-bar F, working in the ways formed by the elevated part D' and engaging the pinion E', and a lever for working the rack-bar, as set forth. 80

2. In a washing-machine, the combination, 85 with the tub suitably supported and having a cover made in sections, of the plate or casting D, fitted to one of the cover-sections and formed with a raised part or elevation, D', and an extension or arm, D'', the shaft E, carrying the agitator within the tub and provided with a pinion, E', at its upper end, a rack-bar, F, moving in the ways formed by the elevation D' and engaging with the pinion E', a pitman, G, connecting with the rack-bar, a plate, H', secured to the bottom of the tub, a lever, H', fulcrumed in the plate and connected to the pitman, and an operating-handle, H, for the lever, as and for the purpose set forth. 90

In testimony whereof I affix my signature in presence of two witnesses.

ALFRED T. JACKSON.
